Specification for Design.

Patented Nov. 29, 1921.

Application filed January 10, 1921. Serial No. 436,358. Term of patent 14 years.

To all whom it may concern:

Be it known that I, ELISHA A. PHINNEY, a citizen of the United States, and a resident of Pawtucket, in the county of Providence and State of Rhode Island, have invented a new, original, and ornamental Design for Watch-Bows, of which the following is a specification, reference being had to the accompanying drawing, forming part thereof.

In this drawing, the figure is a plan view of the watch bow.

I claim:—

The ornamental design for a watch bow, as shown.

In testimony whereof, I affix my signature in the presence of two witnesses.

ELISHA A. PHINNEY.
